M. F. HYDE.
SODA WATER APPARATUS.

No. 12,485.

Patented Mar. 6, 1855.

UNITED STATES PATENT OFFICE.

MARCUS F. HYDE, OF BURLINGTON, NEW JERSEY.

SODA-WATER APPARATUS.

Specification of Letters Patent No. 12,485, dated March 6, 1855.

To all whom it may concern:

Be it known that I, MARCUS F. HYDE, of Burlington, in the county of Burlington and State of New Jersey, have invented a new and Improved Apparatus for Making Soda and other Mineral Waters; and I do hereby declare that the following is a full and exact description.

The nature of my invention consists in employing three strong vessels of cast iron or other substance enameled on the inside A, B, C, connected as described by an iron pipe also enameled on the inside, two of which vessels A and B being cast in one piece, are used as generator and purifier as hereinafter described, and the other C as condenser, and the water charged with gas by its own pressure in connection with a porous disk attached to the end of the pipe E.

To enable others skilled in the art to make and use my invention, I will proceed to describe its construction and operation.

Three cylinders A, B, and C, are made of iron or other substance of sufficient strength to sustain a pressure of from seventy-five to one hundred pounds pressure to the inch; of which the two smaller, the generator and purifier A and B are about ten inches in height and five in diameter, and the other the condenser C, proportioned in size to the quantity of water to be carbonated. The head D of the larger is fitted on gas tight (for the smallest leak will destroy the perfection of the carbonization) in any of the usual methods; or the cylinder may be formed of two halves with flanges united in the middle. The two cylinders, generator, and purifier are cast in one piece and their connecting pipe cast in the iron between them as represented in drawing. Through the head D of the condenser passes a pipe E from the purifier B to within one or two inches of the bottom also screwed in gas-tight; on the end of which pipe is fastened a disk F of fine iron wire gauze or other equivalent porous substance.

The generator has a head G such as represented in its drawing, having in it a safety valve H, so constructed that to the screw rod passing through it a perforated lead basket K is attached for holding the alkali, and also to allow the head to be taken off

when the water is charged, without further consumption of material; there is also a lead jar L placed in the generator for holding the dilute acid. The purifier B is filled to nearly the pipe E with alkaline water, or water merely. P is a screw valve in the purifier for filling it.

N is a screw valve in the condenser for filling, and also to remove atmospheric air from it after the charging has commenced; D, pipe to ascertain the height of water in condenser before charging with gas; L, 65 cock to remove contents from condenser and to clean it.

The operation of the fountain is as follows; the condenser C having been filled with water to cock O, and the purifier to 70 nearly pipe E, the alkali-bicarbonate of soda well wrapped up in paper, so that a few seconds may elapse before the acid acts upon the alkali, is placed in the lead basket K attached to the rod passing through the 75 head of the generator; the head is then put on and screwed down tight. The gas generated then passes down the pipe M cast between the generator and purifier, through the semi-liquid or liquid in the purifier, and through 80 the connecting pipe E to the bottom of the condenser C, and coming in contact with the finely perforated disk F, is minutely subdivided, and in that condition passes up the water until it is thoroughly carbonated. 85 When this takes place the cock R is turned, and the connection between the generator and condenser is cut off and the head of the generator, to save further expense of alkali is taken from its place. Then by turning 90 the cock S the water may be drawn. Any amount of pressure may be obtained in this way without the use of a forcing pump, as ordinarily used for charging water with carbonic acid gas, for the chemical action 95 will go on under whatever pressure till the materials are spent.

What I claim as my invention, and desire to secure by Letters Patent is—

The porous distributor or its equivalent 100 arranged and operating as described.

MARCUS F. HYDE.
